UNITED STATES PATENT OFFICE.

MAX SCHAFFER, OF NEW YORK, N. Y.

DESIGN FOR A GLASS BOWL.

47,652.

Specification for Design.

Patented July 27, 1915.

Application filed March 27, 1915. Serial No. 17,561. Term of patent 3½ years.

To all whom it may concern:

Be it known that I, MAX SCHAFFER, a citizen of the United States, residing at 2116 Vyse avenue, borough of Bronx, county of Bronx, and State of New York, have invented a new, original, and ornamental Design for a Glass Bowl, of which the following is a specification, reference being had to the accompanying drawing, forming a part thereof.

Figure 1 shows a side elevation of my invention, Fig. 2 shows a plan view of my invention.

I claim:

The ornamental design for a glass bowl, as shown.

MAX SCHAFFER.

Witnesses:

PERRY ANSERP,
BENJ. ROSEN.
